UNITED STATES PATENT OFFICE

ROBERT D. DUNCAN, JR., OF EAST ORANGE, NEW JERSEY, ASSIGNOR, BY MESNE ASSIGNMENTS, TO FEDERAL TELEGRAPH COMPANY, A CORPORATION OF CALIFORNIA

THREE-PHASE WIRED RADIO RECEIVING CIRCUITS

Original application filed June 5, 1925, Serial No. 35,212, now Patent No. 1,592,085, dated July 13, 1926. Divided and this application filed April 20, 1926. Serial No. 103,339.

My invention relates broadly to carrier wave signaling systems and more particularly to a receiving system for carrier wave line wire operation.

5 This application is a division of my United States Patent Number 1,592,085, issued July 13, 1926.

One of the objects of my invention is to provide a circuit arrangement for wired radio receiving systems whereby stray electromagnetic fields or radiation from the line wires over which the high frequency currents are conveyed are substantially negligible thereby eliminating the inherent disadvantages 15 which exist where wired radio signals are thrown open to reception over space radio systems.

Another object of my invention is to provide a circuit arrangement for wired radio receiving systems whereby a plurality of receiving apparatus connecting with the different phases of a polyphase transmission line receive substantially equal amounts of high frequency energy by virtue of polyphase high 25 frequency transmission and of phase reversing circuits at the receivers.

Still another object of my invention is to provide a wired radio receiving system where received currents at a plurality of receiving 30 stations connected along a carrier wave line wire distribution system may be effectively impressed upon translating circuits with relatively large signal intensity by virtue of polyphase transmission.

35 A still further object of my invention is to provide a receiving circuit arrangement for wired radio systems where the effective energy impressed upon the translating circuit may be considerably augmented by transmitting and receiving three phase carrier wave energy.

40 My invention contemplates the arrangement of inductances in coupled relation at a receiving station for so reversing the phases of polyphase signaling currents that the several phases are vectorially added to effectively operate the translating device at the wired radio receiver.

45 In high frequency carrier current communication and broadcasting systems in

which the high frequency current is superimposed on electric lighting and power lines, it has been determined that when the latter form a part of a three phase transmission system, which is the case in practically all of the modern power systems, the generation and utilization of three phase high frequency current rather than single phase high frequency current is accompanied by a number of advantages. The principal advantages 55 are a uniform and even high frequency current distribution over the power lines, and the practical complete elimination of stray electromagnetic fields or radiation from the lines. The reason for the latter is that the currents in the three phases differ in phase by 120 degrees and in accordance with fundamental electrical theory at any instant their sum is zero or their combined effect upon an external receiver is nil. 70

In my Patent No. 1,578,881, dated March 31, 1926, and in my co-pending application Serial No. 61,019, filed October 7, 1925, and my United States Patent Number 1,643,405 issued September 27, 1927, I have shown a 75 new and novel method for generating high frequency current at polyphase and in particular three phase. In Letters Patent 1,560,505, dated November 3, 1925, I have illustrated one of the applications of polyphase high frequency signaling systems using a high frequency current source similar to that which may be employed in my present system. In long distance high voltage power transmission three phase carrier current operation is especially beneficial. It is also possible by proper and suitable arrangement of receiving apparatus to derive additional benefits from three phase high frequency operation. 85

90 In the embodiment of the invention herein claimed a distinct advantage is to be found over the invention covered by my Patent 1,592,085. This advantage resides in the discovery that the polyphase receiving circuit may be coupled through only two windings with the three phase circuit which connects to the line wire system. One of the coils in the three phase line wire circuit is 95 free of coupling relationship to the coils in 100

the receiving circuit proper and yet it is found that the currents in the several windings may be vectorially added to operate the responsive device.

- 5 Thus it is possible in carrying out the present invention to dispense with the coupling between the receiving circuit and one of the windings of the three phase transmission system.
- 10 My invention will be more clearly understood by reference to the accompanying drawings, in which:

Figure 1 is a diagrammatic view showing the arrangement of a wired radio receiving set operating in conjunction with a three phase power distribution line upon which three phase carrier wave signaling current is impressed: Figs. 2 and 3 are vector diagrams showing the characteristics of the signaling currents in the three phase carrier wave system and in the wired radio receiving circuit which I provide for connection to the three phase transmission line.

Referring to the drawings in detail, reference character 1 in Fig. 1, represents a power house or substation; reference characters 2, 3 and 4 show three transmission lines forming a three phase power system leading from the power house 1, and reference letter 5 indicates a receiving power substation connected with the transmission line. Connected to the three lines 2, 3 and 4, through coupling condensers 6, 7 and 8, is a three phase high frequency generating source 9, which supplies modulated high frequency current to the lines. Suitable means are provided in association with the high frequency generating source 9 for effecting modulation by voice or for forming telegraphic signals. Connected to the line through condensers 10, 11 and 12 at any desired points along the line adjacent the receiving end are inductance coils 13, 14 and 15 which are shown to be interconnected in star or Y. Inductively coupled to two of these coils, for example, 13 and 14, is a series circuit made up of inductance coils 16 and 17 and capacity 18. The capacity 18 may or may not be variable. Inductances 16 and 17 are substantially identical in construction and have approximately the same number of turns wound in the same direction. Coils 16 and 17 are connected in reverse manner, however, as illustrated. The receiving circuit contains a suitable translating device for observing the received signals. A crystal detector 19 is shown connected in the receiving circuit with telephone receivers 21 shunted by condenser 20.

The operation of the system as illustrated in Fig. 1, may be explained with the assistance of the vector diagrams of Figs. 2 and 3. The three phase high frequency signaling currents, modulated or unmodulated, established in the lines 2, 3 and 4 by generator 9, cause to flow in the three phase coils 13, 14 and

15 three equal currents I_1 , I_2 , I_3 , differing in phase by 120 degrees as indicated in Fig. 2. The magnetic field established by coils 13 and 14 induce voltages in coils 16 and 17 which give rise to currents I_1^1 and $(-I_2^1)$. The current $(-I_2^1)$ is displaced 180 degrees from I_1^1 by virtue of the reversed connection of coil 17 and with respect to coil 16. The resultant current in circuit 16, 17 and 18 which may or may not be tuned to resonance, is the vector sum of I_1^1 and $(-I_2^1)$ and is equal to $\sqrt{3}$, or 1.732 times either I_1^1 or $(-I_2^1)$ due to the fact that the phase angle between these currents has been changed from 120 degrees to 60 degrees. The value of the effective current is therefore indicated at I' which is the vector sum of I_1^1 and $(-I_2^1)$. This effective current I' actuates the translating circuit containing detector 19 and telephones 21.

By methods shown in Fig. 1, the use of three phase high frequency signaling energy for carrier operation over high voltage power lines is made possible with its accompanying advantages of substantially non-radiation and increased signal strength which polyphase reception makes possible as compared with single phase reception. It will be observed that the effective received current which actuates the translating circuit is represented by the vector I' in Fig. 3 and that the value thereof is substantially greater than the current value which could be effectively secured by merely coupling the receiving circuit to the line in a single phase system.

It will be noted that a reversed connection is shown at inductance 17, Fig. 1. It is obvious that an equivalent effect can be obtained with inductance 17, symmetrically connected with the remaining inductances of the circuit containing them, but with their direction of winding reversed from that of the remaining inductances. This change obviously falls within the scope of this invention, since the essential requirement is that of obtaining substantially a complete phase reversal of one of the component currents established in the circuit containing inductances 16 and 17 of Fig. 1.

With regard to the theory of the circuits shown, it should be noted that the reversed connection of coil 17 is to obtain a complete phase reversal of the component of current induced in this coil. This phase reversal may be accomplished either by reversal of connections as shown, or by symmetrical connection of the coils but reversed in the direction of winding of the same, as hereinbefore pointed out. By virtue of this reversal the resultant vector current of circuit 16, 17 and 18 of Fig. 1 is substantially equal to $\sqrt{3}$ times either of the individual component currents induced through coupling coils 13—16 and 14—17, said component currents, of course being equal under symmetrical conditions of coil construction and coupling.

While I have described my invention in a particular embodiment, I desire that it be understood that modifications may be made and that no limitations upon the invention are intended other than are imposed by the scope of the appended claims.

What I claim as new and desire to secure by Letters Patent of the United States is as follows:

- 10 1. A wired radio communication system comprising a line circuit, for conveying three phase signaling energy, means including independent inductances connected to each of the phases of said line circuit, a translating circuit, said translating circuit including a pair of oppositely connected inductance coils, each coil being independently coupled to one of said inductances and a signal observing circuit connected with said translating circuit for vectorially adding the effect of the signaling energy.
- 15 2. A wired radio receiving system comprising a three phase electric power transmission line carrying superimposed three phase high frequency current, three substantially equal inductances, one of said inductances being connected in each phase of said transmission line, two additional inductances symmetrical-
20 ly coupled to two of said first mentioned in-
ductances and connected in series in an op-
posing manner, the remaining of said first
mentioned inductances being remote from
coupled relationship with respect to said two
additional inductances, a translating and sig-
30 nal indicating means associated with said ad-
ditional inductances, the coupling between
said additional and first mentioned induct-
ances being such that the resultant current in
said additional inductances is vectorially add-
40 ing.
- 35 3. A wired radio receiving circuit comprising in combination a three phase line wire circuit, an inductance connected to each phase of said line wire circuit, a polyphase receiv-
45 ing circuit, and a pair of coils disposed in said receiving circuit and coupled with two of said aforementioned inductances and arranged to vectorially add the current components in said polyphase receiving circuit for operat-
50 ing an indicator device, one of said first men-
tioned inductances being free of coupling re-
lationship with said pair of coils.
4. A wired radio receiving system comprising in combination with a three phase line
55 wire circuit, an inductance connected in each phase of said circuit, a three phase receiving circuit, a pair of coils connected with said three phase receiving circuit and coupled with all but one of the inductances in said
60 line wire circuit, a rectifying device, a responsive device, and connections therebetween for vectorially adding the effects of current com-
ponents in said three phase receiving circuit upon said rectifying device.
